UNITED STATES PATENT OFFICE

2,336,127

HYDROTHERAPY APPARATUS FOR FEET

William Rocke, South Bend, Ind.

Application September 29, 1941, Serial No. 412,796

14 Claims. (Cl. 4—180)

This invention relates to a hydrotherapy apparatus, and particularly to a special form of such a device for treating feet and legs. It is a continuation in part of my application Serial No. 392,646, filed May 9, 1941, now Patent No. 2,280,979, granted April 28, 1942, for Hydrotherapy circulator, which utilizes the apparatus described and claimed in my Patents Re. 20,424 and 2,250,315.

The particular object of this invention is to provide a hydrotherapy apparatus for treating feet and legs which will create circulating water currents from an annular discharge orifice into which air may be injected in variable amounts to create uniformly distributed currents discharged radially outwardly to provide means to variably massage the feet by varying the position of the feet in relation to the discharge orifice and the amount of injected air.

Other objects and benefits will be disclosed in the following descriptions and drawings, in which:

Fig. 1 is a cross sectional elevational view of a preferred form of my device mounted in a cabinet; and

Fig. 2 is an enlarged broken end elevational view, partly in section, of the apparatus as it would appear on the section line 2—2 of Fig. 1 with the patient's feet being treated by water and air currents, as will later be explained.

Now referring to Fig. 1, showing a preferred embodiment of my invention, I provide a relatively low cabinet 10 in which I mount a tub 11 having a perforate partition 12. In the bottom of the tub 11 I mount my centrifugal pump 13 which has an annular discharge orifice 14 above the partition 12. An air inlet tube 15 is mounted centrally on the pump casing and at its top is a valve 16 for controlling the flow of air. The section of the cabinet over the tub is closed by a lid 17 hinged at 18, and it will be understood that the tub 11 may be uncovered by swinging the lid 17 outwardly. The pump is driven by a motor 19 through a conventional belt and pulley drive 20. The motor side of the cabinet is covered by a lid 21 supported by the hinge 22. It will be understood that by this arrangement the lid 21 forms a convenient seat for the patient, who places his feet in the tub 11. The lid 21, when opened outwardly, uncovers a convenient supply compartment 23.

Now referring to Fig. 2, my centrifugal pump 13 has been fully described in my previous applications and patents, and for the purpose of this disclosure will not be described in detail. It will be observed that the annular orifice 14 is located above and closely adjacent the partition 12 which has an annular inlet opening 12a around its outer rim to permit inlet water to flow to the pump 13. The air inlet tube 15 is mounted on top of the

pump housing by any conventional means and is provided with a conventional rotating valve 16 wherein the outer shell of the valve is provided with openings 16a communicating with opening 16b in the tube 15. It is understood that by rotating the valve 16 air in variable amounts may be permitted to flow through the tube 15 or, at the will of the operator, the air may be completely shut off. The downwardly flowing air through the tube 15 flows through annular openings 24 and the thin, flat passageway 25 immediately under the flat top of the pump 13 to an annular injector jet 26 overhanging and closely adjacent the annular discharge orifice 14. As is well understood in the art, this is the well known injector principle wherein the vacuum created by the outwardly flowing water currents through the orifice 14 induces a flow of air through the orifice 26. It will be appreciated that the annular orifices 14 and 26 provide a structure which induces radially outward water currents over the partition 12 which flow upwardly, then inwardly and downwardly in the center of the tank. This flow is shown diagrammatically by arrows in the left half of the tank in Fig. 2. On the right half of the tank in Fig. 2 I show diagrammatically how air through the orifice 26 is injected into these water currents and how air generally follows the course of these currents. As has heretofore been explained, the volume of air is controlled by the valve 16, and this variable flow of air in the water currents provides a variable massaging effect, as is well understood in the art.

At F—1 I show the patient's foot held angularly on the partition 12 with the bottom of the foot and the outward sides of the legs subjected to heavy water currents. At the right-hand side, at F—2, I show the patient's foot supported by the platform formed by the flat top of the housing of the pump 13, close to the air tube 15 and with a large volume of air being induced into the water currents. It will be appreciated that the bottom of the foot, F—2, is now being subjected more to suction than to pressure, with the leg and foot more gently massaged by the flow of lighter water currents and air bubbles. It will also be appreciated that many combinations of positions between the two described are available, and further that the tub 11 may be varied in depth to provide treatment for the entire leg if necessary, with the water line W—L being adjusted to suit these variable conditions. Under some of these conditions I may desire to eliminate the central air tube 15, and this can readily be done as, for instance, by providing a rubber tube which may be positioned closely adjacent the side of the tank, out of the way of the patient.

From the foregoing description it is apparent that I have provided a hydrotherapy device for treating feet and limbs wherein variable massag-

ing effects may be accomplished by adjustments readily available to the operator.

Having thus described my invention, I now claim as new:

I claim:

1. In a hydrotherapy device, a water tank, a perforate partition near the bottom of the tank, a centrifugal pump mounted in the bottom of the tank having an inlet below the partition and a ring discharge orifice for divergent water currents above the partition, an annular air inlet in injection relationship to the discharge orifice, and means to convey air to the air inlet.

2. In a hydrotherapy device for feet, a cabinet including a seat, a water tank in said cabinet adjacent the seat, a perforate partition near the bottom of the tank, a centrifugal pump mounted in the bottom of the tank having an inlet below the partition and a ring discharge orifice for divergent water currents above the partition, an annular air inlet in injection relationship to the discharge orifice, means to convey air to the air inlet, and valve means within reach of a seated patient for controlling the flow of air.

3. In a hydrotherapy device for feet, a cabinet including a seat, a water tank in said cabinet adjacent the seat, a perforate partition near the bottom of the tank, a centrifugal pump mounted in the bottom of the tank having an inlet below the partition and a discharge orifice above the partition, a pump drive motor mounted within the cabinet, an air inlet in injection relationship to the discharge orifice, and means to convey air to the air inlet.

4. In a hydrotherapy device for feet, a cabinet including a seat, a water tank in said cabinet adjacent the seat, a perforate partition near the bottom of the tank, a centrifugal pump mounted in the bottom of the tank having an inlet below the partition and a discharge orifice above the partition, a pump drive motor mounted within the cabinet, an air inlet in injection relationship to the discharge orifice, means to convey air to the air inlet, and valve means within reach of a seated patient for controlling the flow of air.

5. In a hydrotherapy device for feet, a water tank, a centrifugal pump mounted adjacent the bottom of the tank having divergent discharge orifices, air inlets in injection relationship to the discharge orifices, means to convey air to the air inlets, and valve means for controlling the flow of air whereby diverging water currents of variable intensities are created.

6. In a hydrotherapy device, a water tank, a centrifugal recirculating pump mounted in the bottom of the tank having a guarded inlet and a ring discharge orifice, an annular air inlet in injection relationship to the end of the discharge orifice, and means to convey air to the air inlet.

7. In a hydrotherapy device for feet, a cabinet including a seat, a water tank in said cabinet adjacent the seat, a centrifugal pump mounted in the bottom of the tank having a guarded inlet and an annular discharge orifice, a ring air inlet in injection relationship to the end of the discharge orifice, means to convey air to the air inlet, and valve means within the reach of a seated patient for controlling the flow of air whereby variable massage effects are available to the patient.

8. In a hydrotherapy device for feet, a cabinet including a seat, a water tank in the cabinet

adjacent the seat, a centrifugal pump mounted adjacent the bottom of the tank, a pump drive motor mounted within the cabinet under the seat, a discharge orifice from the pump for divergent water currents, air inlet means in injection relationship to the discharge orifice, and valve means accessible to the seated patient for controlling the flow of air whereby variable massage effects are available to and under control of the patient.

9. In a hydrotherapy device for feet, the combination with a water tank, of a recirculating pump having a water discharge orifice in the tank, and an air conduit having an air discharge orifice in injector relation with the water discharge orifice for forcing air discharge therefrom and mixture with the water by the force of the water discharge.

10. In a hydrotherapy device for feet, the combination with a water tank having a perforate partition near the bottom thereof, of a pump mounted in the bottom of the tank with an inlet below the partition and a discharge orifice above the partition in the tank, and an air conduit having an air discharge orifice in injector relation with the water discharge orifice for forcing air discharge therefrom and mixture with the water by the force of the water discharge.

11. In a hydrotherapy device for feet, the combination with a water tank, of a recirculating pump mounted in the bottom of the tank and including a pump housing having a water discharge orifice, said housing having an air passageway through the upper portion thereof to a point in close proximity to the water discharge orifice in injector relation therewith.

12. In a hydrotherapy device for feet, the combination with a water tank, of a recirculating pump mounted in the bottom of the tank and including a pump housing having a peripheral water discharge orifice, said housing having an air passageway through the upper portion thereof with a peripheral air discharge opening in close proximity to the water discharge orifice in injector relation therewith.

13. In a hydrotherapy device for feet, the combination with a water tank, of a recirculating pump mounted in the bottom of the tank and including a pump housing having a peripheral water discharge orifice, said housing having an air passageway through the upper portion thereof with a peripheral air discharge opening in close proximity to the water discharge orifice in injector relation therewith, said pump housing having a downturned peripheral flange projecting downwardly approximately over the air discharge opening to deflect the air therefrom into the water discharge.

14. In a hydrotherapy device for feet, the combination with a water tank, of a recirculating pump mounted in the bottom of the tank and including a pump housing having a peripheral water discharge orifice, said housing having an air passageway through the upper portion thereof with a peripheral air discharge opening in close proximity to the water discharge orifice in injector relation therewith, and an air tube extending upwardly from the pump housing and communicating with the air passageway, said housing having a flat top around the air tube forming a platform for supporting the feet.

WILLIAM ROCKE.
